OF DETROIT, MICHIGAN.

BUILDING-TILE.

1,175,875.

Specification of Letters Patent. Patented Mar. 14, 1916.

Application filed April 3, 1913. Serial No. 20,033.

To all whom it may concern:

Be it known that I, Thomas E. Shields, a citizen of the United States of America, residing at Detroit, in the county of Wayne and State of Michigan, have invented certain new and useful Improvements in Building-Tiles, of which the following is a specification, reference being had therein to the accompanying drawings.

10 The invention relates to tiles such as are used in the construction of floors, ceilings, division walls, etc., in buildings, and it is the object of the invention to obtain a construction which possesses a greater strength 15 and a stronger interlock than constructions heretofore used.

In the drawings: Figure 1 is a cross section through a portion of a floor formed of my improved construction of tile; Fig. 2 20 is a similar view showing a slightly modified construction; Fig. 3 is a perspective view of one of the detached tiles; and Fig. 4 is a view similar to Fig. 1 showing another modification.

25 In the construction of floors and ceilings in fire-proof buildings, it is common practice to employ hollow tiles, which span the spaces between adjacent joists or beams, and are suitably interlocked to form supporting 30 arches. With such constructions the stresses which are developed under load are not uniformly distributed, some of the tiles being subjected to much greater stress than the others, and as a consequence all of the tiles 35 must be of sufficient weight and size to take care of the maximum stress. With my improved construction the tile is so designed that in whatever position it may be placed in the structure there is an advantageous 40 disposition of the material to carry the stresses to which it is subjected. More specifically the structure is such as to produce a latticed bracing, while in reverse position adjacent tiles have their braces in longitudinal alinement, so that the stresses may be 45 carried continuously therethrough.

Another feature of the invention is the construction of the interlock between adjacent tiles, which is of a substantially S-shaped form, making both a stronger structure and one less liable to change its shape during the baking process. Also any slight irregularities will not interfere with the interlocking engagement.

50 As shown in Fig. 1, A is the bottom, which

is reinforced concrete having metallic tension members B embedded therein. C is my improved tile, which in external contour is such as to fit against an adjacent tile when in reverse position. Preferably so this external contour in general shape is that of an ogée curve, the convex portion of one tile fitting into the concave portion of a reverse tile.

As is usual the tile is hollow, the external 55 walls having substantially parallel outer and inner faces. These walls are then braced by diagonal or latticed bracings D E, so that the load upon the arch will be transmitted through these braces substantially 70 longitudinally thereof. In the construction shown in Fig. 1, pairs of braces D D' and E E' are arranged in each tile, and the construction is such that the braces D of one tile will be in alinement with the braces D' 75 of the adjacent reverse tile, and in the same manner the braces E of the first tile will be in alinement with the braces E' of the second tile. Thus the center tile C' which has its wide side at the top will transmit 80 its load to the diagonal braces thereof, which being alined with the diagonal braces of the adjacent tiles, will carry the stresses downward toward the base of the supporting beam. In other words, an arch is produced 85 with straight lines of stress from the center diagonally downward to the opposite sides.

The construction shown in Fig. 2 is designed for use where the depth of the floor is not sufficient for a pair of braces in each 90 tile. This construction is, however, provided with oppositely-inclined latticed braces which operate to carry the load diagonally downward.

To form an interlock between adjacent 95 tiles, I have provided a tongue-and-groove engagement, and this is preferably formed by a similar S-shaped curve F. This has the advantage that there are no sharp corners to form lines of weakness or to become 100 broken off, and at the same time when the adjacent tiles are interlocked they will be securely held from relative lateral movement.

The top and bottom faces of the tile may 105 be finished in any suitable manner, but as shown the wide face G is complementary to the narrow face H, and each is provided with a series of grooves I for interlocking with the ceiling which forms the floor.

While I have described the construction of a floor, it is obvious that the same is applicable to a ceiling or a roof and in the construction of partitions. In all of these structures there will be the same bracing effect of one tile upon the adjacent tile, and the carrying of transverse stresses diagonally from the center of the span to the point of anchorage.

10. It will be noted that in specific form my improved tile comprises a flat side, an opposite arched side and transversely-extending sides with diagonal braces therebetween.

15. In the building of ceilings it is often desirable to make provision for electrical conduits which are accessible. Such a conduit may be formed by providing tiles such as J Fig. 4, in which the arch portion C' is omitted, so that a channel K is left. This will not interfere with the strength of the structure to any material extent, as the diagonal braces remain intact and coöperate with those of the adjacent tiles.

25. What I claim as my invention is:—

1. In a building structure, a series of tiles of the same form alternatively reversed and engaged with each other, each of said tiles being provided with a pair of diagonal braces extending between the opposite side walls thereof, and the abutting faces of adjacent tiles having S-shaped interlocking portions between said braces.

2. In a building structure, a series of tiles of the same form alternatively reversed and engageable with each other in such position, each of said tiles being provided with a pair of substantially parallel diagonal braces alining with the diagonal braces of the reverse tile and the abutting faces of adjacent tiles having an S-shaped interlock between said diagonal braces.

3. In a building construction a series of tiles of the same form alternately reversed and engageable with each other in such position, each of said tiles being provided with diagonal braces between the side walls thereof adapted to aline with the braces of the adjacent tile, and one of said tiles being cut-away beyond the braces to form a conduit.

4. In a building construction, a plurality of interchangeable tiles alternately in reverse positions and having complementary external contours, said tiles having oppositely inclined diagonal braces between the opposite side walls and S-shaped portions in their abutting contours intermediate said diagonal braces forming an interlock.

In testimony whereof I affix my signature in presence of two witnesses.

THOMAS E. SHIELS.
